ATTORNEY

UNITED STATES PATENT OFFICE.

SIMON J. LEVY, OF NEW YORK, N. Y.

TROUSERS-HANGER.

SPECIFICATION forming part of Letters Patent No. 673,686, dated May 7, 1901.

Application filed August 26, 1899. Serial No. 728,586. (No model.)

To all whom it may concern:

Be it known that I, SIMON J. LEVY, a citizen of the United States, residing at New York, in the county of New York and State of New York, have invented certain new and useful Improvements in Trouzers-Hangers; and I do hereby declare the following to be a full, clear, and exact description of the invention, such as will enable others skilled in the art to which it appertains to make and use the same.

This invention relates to an improvement in trousers-hangers; and it consists in the construction, arrangement, and combination hereinafter described.

The invention is designed for use in connection with creased trousers, and is intended for application in such a manner as to preserve the crease and hold the trousers in a proper position and shape when suspended from a hook or peg. Pressing the trousers and using clamps on the lower parts of the legs is one method now adopted; but the inconvenience and trouble incident to this method are obvious and generally recognized. My invention is designed to avoid such objections.

In the drawings I have shown in Figure 1 the invention applied, in Fig. 2 the hanger separated from the trousers, and in Fig. 3 a front elevation of a pair of trousers with the hanger applied ready to be placed on a hook or peg.

In the drawings, A designates a pair of creased trousers, the crease being designated at a, which, as is usual, extends from or in line with the first suspender-buttons B in front on opposite sides of the opening b of the trousers.

C designates the hanger, which is conveniently in the form of a chain, the length of which being conveniently, but not necessarily, equal to the distance between the two buttons B, as shown in Fig. 3. This hanger strip or chain has at opposite ends suitable attaching

devices, which, as shown, are formed with enlarged circular portions d and narrow portions d' of a well-known construction, the buttons being passed through the large portion d and the shank or securing threads drawn into the reduced portions. This form of attachment renders the same removable, so that the hanger can be readily applied and removed from the trousers. Any desirable form of device can be employed for detachably securing the hanger-strip to pass over the head of the buttons.

In use the ends of the hanger-strip are secured to the buttons, and as the buttons B are in line with the creases a the draw or weight is suspended in line with or along the creases, allowing the trousers to be properly folded along the lines of creases, and thereby preserving the shape and crease.

Having thus described my invention, what I claim as new, and desire to secure by Letters Patent, is—

1. A hanger for trousers, consisting in a short flexible strip having at each end loops formed with keyhole-slots therein, adapted to be fitted over and secured to a button, substantially as described.

2. A trousers-hanger consisting of a flexible strip of a length to extend from one suspender-button in front to the adjacent button on the opposite side of the front opening of the trousers, and having fixedly secured to the opposite ends attaching devices having enlarged portions to fit over the buttons and narrow portions to engage under the buttons, substantially as described.

In testimony whereof I affix my signature in presence of two witnesses.

SIMON J. LEVY.
